UNITED STATES PATENT OFFICE.

ANNA STENSLAND, OF BROOKLYN, NEW YORK.

BUST SUPPORTER AND REDUCER.

1,115,034.

Specification of Letters Patent. Patented Oct. 27, 1914.

Application filed April 8, 1914. Serial No. 829,161.

To all whom it may concern:

Be it known that I, ANNA STENSLAND, a citizen of the United States, and residing at Brooklyn, in the county of Kings and State 5 of New York, have invented certain new and useful Improvements in Bust Supporters and Reducers, of which the following is a specification, such as will enable those skilled in the art to which it appertains to 10 make and use the same.

This invention relates to what are known as bust supporters and reducers, and the object thereof is to provide an improved device of this class which may be conveniently 15 applied and worn, and which is simple in construction, efficient in operation, and comparatively inexpensive.

My improved bust supporter and reducer is used in connection with an ordinary cor- 20 set, and the invention is fully disclosed in the following specification, of which the accompanying drawing forms a part, in which the separate parts of my improvement are designated by suitable reference characters 25 in each of the views, and in which;

Figure 1 is a front view of a form shown only in outline and provided with a corset, and showing the method of using my improvement;—Fig. 2 a partial section on the 30 line 2—2 of Fig. 1;—Fig. 3 a sectional view of one side of the corset and showing the means employed for securing the ends of the bust supporter and reducer under the arms, or at the opposite sides of the corset;—Fig. 35 4 a back view of my improvement detached, and;—Fig. 5 a face view of a securing tab one of which is secured to each side of the corset.

In the drawing forming part of this speci- 40 fication, I have shown at *a* an ordinary corset on a form which is shown only in outline, and at *b* I have shown my improved bust supporter and reducer, a back view of which is given in Fig. 4.

The general form of my improvement is 45 clearly shown in Figs. 1 and 4, and it com- 50 prises a central body portion of predetermined width both the top and bottom edges of which are tapered toward the ends *b*² which are comparatively narrow and provided with studs *c* which are secured thereto in the usual or any preferred way, and secured to the opposite sides of the corset, and prefer- 55 ably in positions directly under the arms,

when the corset is in use, are tabs *d* having 55 hook members *e* adapted to be engaged by the studs *c*. My invention however, is not limited to the use of the studs *c* and hook members *e* for securing the ends of the bust supporter and reducer, and ordinary hook 60 and eye devices, or buttons may be employed, if desired.

The top edge of the body portion of the device is preferably depressed centrally as shown at *b*³, to give the desired shape there- 65 to and the bottom edge is preferably correspondingly projected, as shown at *b*⁴, and said device is provided with a plurality of vertically arranged, or approximately vertically arranged stays *f*, any desired num- 70 ber of which may be employed, and secured approximately centrally of the opposite side portions of the device are hooks *g* which are adapted to engage the top edges of the cor- 75 set *a*, as clearly shown in Fig. 2.

The position of the top edge of the corset, when in use, is indicated by the dotted lines *a*² in Fig. 1, and clearly shown at *a*² in Fig. 2, and the vertical width of my improved bust supporter and reducer and the position 80 of the hooks *g* are preferably such that the supporter and reducer extends a predetermined distance above and a predetermined distance below the top edge of the corset, and as the bust supporter and reducer may 85 be made of any desired width, the distance that it extends above and below the top edge of the corset, when in use, will, as will be understood, be determined by the dimensions thereof. 90

From the foregoing description it will be seen that my improved bust supporter and reducer extends only part way around the body, the ends thereof being secured beneath the arms, and said device may be quickly 95 and easily placed in position, and as quickly and easily removed whenever desired, and changes in and modifications of the construction described may be made, within the scope of the appended claim, without de- 100 parting from the spirit of my invention or sacrificing its advantages.

Having fully described my invention, what I claim as new and desire to secure by Letters Patent is;—

A bust supporter and reducer, adapted to be worn in connection with a corset and the side portions of which are provided cen- 11

trally of the inner sides thereof with hooks for engaging the top edge of the corset and arranged so that the supporter and reducer will extend above and below said top edge of 5 the corset when in use.

In testimony that I claim the foregoing as my invention I have signed my name in

presence of the subscribing witnesses this 2nd day of April, 1914.

ANNA STENSLAND.
